UNITED STATES PATENT OFFICE

MARTIN E. JOHNSON, OF CHICAGO, ILLINOIS

VISE

Application filed January 7, 1927. Serial No. 159,536.

This invention relates to vises and more particularly to a vise of the bench type adapted for electrical construction work although susceptible of use in other connections.

5 One of the primary objects of the invention
is to provide a device peculiarly adapted for
bending pipe used for electrical conduits and
the like, with the minimum amount of labor
and effort and one so constructed and ar-
10 ranged that successive pieces of pipe may be
bent to the same degree of curvature or to
different degrees of curvature, as desired.

Another object is to provide an auxiliary holding device for the vise for steadying the pipe or other articles being bent or otherwise worked upon, the auxiliary holding device cooperating with the jaws of the vise for the purpose.

Another object is to provide a simple and effective arrangement whereby outlet boxes and the like may be held in the vise without distortion and in such a manner that they may be presented to a worker desiring to ream out any of the several openings usually provided in such articles, or otherwise work upon them as may be necessary or desirable.

23 A further object is to provide a novel form of pipe or rod bending die adapted to bend pipes or rods of various diameters to the proper angular degree. In this connection the die head is arranged with a measuring device whereby the proper length of pipe required for the bend may be measured and determined with a very reasonable degree of 24 accuracy.

Still further objects include the provision of means for adjusting the die head with respect to the clamping jaws of the vise, the provision of means for securing the pipe bending die between the vise parts and against displacement from proper position when being utilized, and the provision of various novel features of construction and arrangement which will be or should become readily appreciated after reading the follow-

ing description and claims and after viewing the drawings in which:

Fig. 1' is a front elevational view of one form of vise constructed in accordance with the preferred form of my invention.

Fig. 2 is a top plan view of the same with the frame member of the vise and its associated parts removed and with the pipe bending die in position for bending a pipe of small diameter.

Fig. 3 is a view similar to that of Fig. 2, showing the pipe bending die in full line position about to be utilized for bending a pipe of slightly larger diameter than the pipe illustrated in Fig. 2, and in dotted line the position of the pipe bending die when disposed in inoperative position.

Fig. 4 is a section taken along the line 4-4 of Fig. 3.

Figs. 5 and 6 are end views of the die head, the first showing a $\frac{1}{2}$ " pipe therein, the second showing a $\frac{3}{4}$ " pipe therein.

Fig. 7 is a perspective view of a pipe bending member removed from the base of the vice to which it is ordinarily attached.

Figs. 8 and 9 are side and front elevational views, respectively, of the vice, showing the manner in which an outlet box or the like of one type may be secured thereby.

Figs. 10 and 11 are side and front elevational views respectively of the vise showing how the same may be utilized for securing a different type of outlet box or the like.

Fig. 12 is a diagrammatic illustration of the method of measuring the pipe for a pre-determined length of bend, and

Fig. 13 is a geometric illustration of the formation of the die head. The vise chosen for illustration is of the ordinary type having a base 2 adapted to be secured by bolts or the like 3 to a bench, table or other element 4. The base carries the ordinary stationary jaw 5 and a lug 6 adapted to be straddled by a pair of lugs 7 formed integral with one leg 8 of a U-shape frame gen-

erally designated 9 in which a movable jaw 10 is slidably carried by a member 11 operated by a screw 12 threadedly engaging an internally threaded boss 13 centrally of the base 5 of the U, i. e., the top of the frame. A bolt 7 passing through the lugs 6 and 7 pivotally connects the frame 9 to the base. The usual member 14 is utilized for running the member 11 and thus the jaw 10 up and down 10 to and from the stationary jaw 5. This structure is old and per se does not constitute my invention.

Referring for the moment more particularly to Figs. 1 and 8 to 11 inclusive, it will 15 be noted that the portion of the base in which the stationary jaw 5 is mounted is extended as shown at 15 and provided with a transverse slot 16 and a projection 17 providing a shoulder 18. The leg or arm 19 of the frame 9 opposite the leg or arm 8 is provided with a downwardly projecting lug 21 adapted to be received, in the slot or recess 16 when the frame is moved about its pivot into cooperative relation with the base and with a dog 22 20 pivotally secured thereto by a bolt or the like 23. The dog is provided with a shoulder 24 providing an abutment adapted to engage beneath and behind the shoulder 18 to secure the frame to the base in the ordinary manner. 25 To the rear of the plane of cooperation of the stationary and movable jaws, that is, to the rear of the vise, a bolt or the like 25 secured in the base, pivotally mounts one end 26 of an arm 27 and also an angle bracket 28 30 for swinging movement thereabout. The vertical side of the angle bracket is drilled for the reception of a pivot bolt 29 on which an arm 31 of a pipe bending die member having a head 32 is pivotally mounted. From 35 the foregoing it will be appreciated that the arm 27 may be swung about the pivot provided by the bolt 25 in one plane and that the die member may be swung about both the pivot 25 and the pivot 29 so that it may have 40 substantially universal movement with respect to the base.

The arm 27 is provided with upstanding lug portions 33 and 34 providing between them a recess 35 adapted to receive a pipe or the like 50 36 and the recess 35 is arranged so that when the arm 27 is in the position shown in Figs. 2 and 3, it will align with the opening between the jaws of the vise. This arrangement is a decided aid in securing the pipe 36 55 against skewing when its outer end is being bent around the die head 32 and in order to reinforce the arm 27 when in the position shown in Figs. 2 and 3, a lug 37 is cast or otherwise secured to the base for abutting engagement with it. The arm 27 may be swung out of the way when large sizes of pipe are being operated upon.

The construction of the die head is shown 60 more clearly in Figs. 5, 6 and 7, from which 65 it will be noted that it is of substantially

sector shape in plan and channel shape in cross-section. The bottom of the channel may be curved, as at 38, on a radius slightly greater than the radius of a $1\frac{1}{2}$ " pipe 36 in order to receive the same, while the outer ends of the channel on their interior surfaces are curved, as shown at 39, on a radius of a $\frac{3}{4}$ " pipe 41. The curved surfaces 39 are, of course, of greater length than the surface 38, since the larger the pipe the greater must be the radius of curvature of a bend made therein. The arm 31 of the die member is adapted to be disposed in the opening provided between the leg or arm 19, the jaw 5 and the extension 15 and to be secured against movement in the direction of its length by an arcuate lug 42 formed integral therewith and adapted to slide laterally of the vise in an arcuate groove 43 formed in the top of the extension 15. Should the pivots 25 and 29 become somewhat worn or loose, the lug 42 engaging in the groove 43 will hold the die and member against displacement.

In Fig. 13 I have illustrated geometrically the formation of the die head from which it will be noted that the inner curve 38 is generated by the circular movement of an arc of a circle "a" at the end of the radius "b" about the point "c" in a direction transverse to the plane of the circle of the arc with the chord of the arc disposed farthest from said point "c", while the interior surface of one side wall of the channel, i. e., the surface 39 is generated by the like movement and disposition of the arc of a circle "x" moving at the end of a radius "y" about a point "z". Of course, "x" is greater than "a", "y" is greater than "b" and the points "c" and "z" are adjacent one another on the same side of the surfaces 38 and 39, that is, to the rear thereof, but are not coincident. From this description it is believed that the relationship of the curves 38 and 39 of the die head may readily be understood. It will be noted that the curved surfaces 38 and 39 are substantially separated at one end of the die head, but merge finally at the end of the die head adjacent the box of the vise, thus forming the channel side walls of two portions, an upper or exterior portion and a lower or interior portion of different curvatures extending for substantially the full length of the channel surface.

It will thus be apparent that the die member is adapted to receive and bend pipes of different diameters when the pipe is held between the jaws and by the member 27, and the die member is secured in position between the arm 19 of the frame and the base of the vise. Since each size of pipe when bent between the points of tangency "A" and "B", as shown in Fig. 3, utilizes a greater length of pipe than the perpendicular distance from either point of tangency "A" or "B" to the other, due allowance must be made when 120 125 130

bending a piece of pipe disposed in the vise jaws, about the die in order that the perpendicular distance from the point of tangency "B" or the end of the pipe adjacent thereto, to a tangent to the pipe at "A", may be whatever is desired. For the purpose of determining the necessary surplus length of pipe which must be allowed and so that succeeding lengths of pipe of the same size may be bent to the same degree and the perpendicular distance between the point of tangency "A" and the point of tangency "B" may be made the same, I have provided indicating means on the upper side of the channel shaped head of the die. This indicating means comprises a lug or projection 44 having a shoulder 45 for measuring pipe of one size, say $1\frac{1}{2}$ " diameter, and a second lug 46 having a shoulder 47 for measuring pipe of a second size, say $\frac{3}{4}$ " diameter. The measurement is accomplished by laying a rule along the pipe from the end of the pipe disposed outwardly of the vise and, depending upon the size of the pipe, abutting the end of the rule against the shoulder 45 or the shoulder 47 and adjusting the pipe in the jaws of the vise until the proper length outwardly of the abutment 46 or the shoulder 47 is obtained.

The manner in which the pipe is measured for the bend, may best be explained by reference to Fig. 12. Assuming that it be desired to bend the pipe 41 from its dotted line position in this figure to its full line position and to have a perpendicular distance "M" between the end "B" and the projection of tangent to the point "A", a rule is abutted against the shoulder 45 of the projection 44 and the pipe 41 moved in the vise jaws until the end "B" is the distance "M" from the shoulder 45. The vise jaws are then tightly clamped on the pipe and the pipe is bent about the die head. The bend when thus made disposes the end "B" at exactly the distance "M" from the line tangent to the point "A". In the same manner the length of $\frac{3}{4}$ " pipe necessary for a right angle bend is determined by measuring from the shoulder 47 on the projection 36. I have sometimes found it desirable to use an adjusting device with the die head when small sizes of pipe are to be bent so that the die may be more closely aligned with the opening between the vise jaws. This adjusting device comprises an arm 56 which is pivotally mounted on the pivot 29 and thereby arranged to swing about the pivot between the position shown in Fig. 2 and a position (not shown) where it lies between the projection 21 and the arm 31. This arm 56 accordingly acts as a spacer and throws the die head 32 further toward the right, viewing Fig. 2.

As has been indicated above, the vise is also arranged so that it may secure a conduit outlet box or the like while it is being worked upon and to this end the dog 22 is

provided with a number of shoulders or teeth 48, 49 and 54 and with a projection 52 integral with that end through which the pivot pin 22 passes. This lug or projection 52 is directed substantially toward the shoulders 48, 49 and 54, as will be noted from Figs. 1, 9 and 11, and serves to engage the interior surface or edge of the flange or the like of a conduit outlet box or the like such as that designated 53. In this instance the flange of the outlet box is of such length that it may be received between the shoulder 48 and the lug 52, and at the opposite side of the outlet box the interior surface of the flange is engaged behind the shoulder 18 formed on the projection 17 of the base so that when a pipe or other rigid article 53' is disposed through the jaws of the vise to provide a fulcrum and the handle member 14 turned to move the movable jaw toward the stationary jaw, the frame 9 will be moved about its pivot 7 and cause the outlet box to be tightly clamped by and between the dog and the shoulder 18. In a like manner the shoulder 49 cooperates with the lug 52 to secure an outlet box 55 having a deeper flange in position to be operated upon for such purposes as reaming out the openings indicated at 56 and 57. The shoulders 54 and 24 may also be utilized to cooperate with the lug 52 for still deeper flanged articles.

From the foregoing it should be appreciated that I have provided a device embodying not only those novel features of construction and arrangement heretofore specifically mentioned but many others obvious or inherent and resulting therefrom. I do not, therefore, desire to be limited to the form of the invention chosen to illustrate my improvement, but only by the spirit of the invention and the scope of the appended claims.

I claim:

1. A pipe vise comprising, a base, a stationary jaw on said base, a frame, a movable jaw mounted in said frame and cooperative with said stationary jaw, a pipe former, a die head on said former adapted to be positioned adjacent and in line with the opening between said jaws, an arm connected to said die head and extending toward the rear of said base, means pivotally securing said arm to said base, so that said head may be swung into and out of said position, and means for securing said head against accidental displacement when in said position.

2. A pipe vise comprising, a base, a stationary jaw on said base, a frame, a movable jaw mounted in said frame and cooperative with said stationary jaw, a pipe former, a die head on said former adapted to be positioned adjacent and in line with the opening between said jaws, an arm connected to said die head and extending toward the rear of said base, and means pivotally securing said

arm to said base, so that said head may be swung into and out of said position.

3. In combination with a pipe vise having a pair of jaws one of which is movable for receiving and clamping a pipe between them, a pipe bending attachment having a head adapted to be disposed adjacent the opening between said jaws at one side thereof, and means on the other side of said jaws pivotally mounting said head so that said head may be swung from one side of said jaws to the other. 75

4. In combination with a pipe vise having a base and a pair of jaws mounted on said base, one of said jaws being movable toward and from the other, a pipe bending member having a head of sector shape adapted to be disposed adjacent the opening between and at one side of said jaws, and means pivotally connecting said head and base together on the other side of said jaws whereby said head may be swung to and from a position adjacent said opening. 15 20 25

5. In combination with a pipe vise having a base and a pair of jaws mounted on said base, one of said jaws being movable toward and from the other, a pipe bending member having a head of sector shape adapted to be disposed adjacent the opening between and at one side of said jaws, means pivotally connecting said head and base together on the other side of said jaws whereby said head may be swung to and from a position adjacent said opening, and releasable means for securing said head against swinging movement about said connecting means when said head is positioned adjacent said opening. 30 35 40

6. In a vise, a base member, a relatively stationary jaw mounted on said base member, a frame member pivotally connected to said base member, a movable jaw mounted on said frame member, said frame member being movable about its pivotal connection toward and from a position where said jaws are cooperable, means for securing said frame member to said base member when said jaws are in cooperative position, an arm secured adjacent said jaws to one side of the plane of their cooperation adapted to be secured by and between said base and frame members when they are secured together, and a pipe bending die head on said arm adapted to be disposed adjacent the opening between said jaws for cooperation therewith for bending a pipe. 45 50 55 60 65

7. In a vise, a base member, a relatively stationary jaw mounted on said base member, a frame member pivotally connected to said base member, a movable jaw mounted on said frame member, said frame member being movable about its pivotal connection toward and from a position where said jaws are cooperable, means for securing said frame member to said base member when said jaws are in cooperative position, an arm pivotally

secured adjacent said jaws and to one side of the plane of their cooperation adapted to be secured by and between said base and frame members when they are secured together, and a pipe bending die head on said arm adapted to be disposed adjacent the opening between said jaws for cooperation therewith for bending a pipe, said arm being movable about said pivot to permit said head to be swung out of cooperative relation with said jaws. 75 80 85

8. In a vise, a base member, a relatively stationary jaw mounted on said base member, a frame member pivotally connected to said base member, a movable jaw mounted on said frame member, said frame member being movable about its pivotal connection toward and from a position where said jaws are cooperable, means for securing said frame member to said base member when said jaws are in cooperative position, an arm secured adjacent said jaws to one side of the plane of their cooperation adapted to be secured by and between said base and frame members when they are secured together, a pipe bending die head on said arm adapted to be disposed adjacent the opening between said jaws for cooperation therewith for bending a pipe, and means for adjusting said die head with respect to said jaws. 90 95 100 105

9. In a vise, a base having a stationary jaw, a frame including a movable jaw pivotally secured to said base for swinging movements into and out of such position with respect to said stationary jaw where said movable jaw will cooperate therewith, means for securing said jaws in cooperative relation, a pipe bending die pivotally secured to the said base for movements bodily toward and from a position adjacent the opening between said jaws and adapted to be secured against movement from such position when said jaws are secured in cooperative relation, and means secured on the opposite side of said jaws from said die for aiding in holding a length of pipe disposed between said jaws against substantial movements in the plane of bending while the same is being bent in said die. 110 115 120 125

10. In a vise, a base adapted to be secured on a bench, a frame pivotally mounted on said base, a projection on said base, a projection on said frame movable with said frame toward and from the projection on said base, said projections having oppositely facing shoulders adapted to engage the interior of a receptacle, and means for moving said projections relatively from one another. 115 120 125

11. In a vise, a base member adapted to receive a relatively stationary jaw, a frame member pivotally connected to said base and adapted to receive a relatively movable jaw, means for moving said frame member about its pivot, a dog on one of said members, a shoulder on the other said member adapted to be engaged by said dog for securing said frame member to said base member and 130

against movement about its pivotal connection, and a shoulder on said dog adapted to cooperate with the first said shoulder to engage interior portions of a receptacle to secure the same.

5 12. A vise dog adapted to be pivotally connected to one of two relatively movable parts of a vise, said dog having a plurality of teeth substantially in a row and a lug adjacent one end projecting substantially in the direction of said teeth.

10 13. A vise dog adapted to be pivotally connected to one of two relatively movable parts of a vise, said dog having a plurality of notches and a pivot opening adjacent one end, and a lug projecting from said end generally toward said notches.

15 14. In a vise as defined in claim 1, the pipe bending die head being of substantially open channel-shape in cross-section and segment shape in plan, the interior surface of the bottom wall of the channel being generated by the circular movement of an arc of a circle "a" at the end of a radius "b" about a point "c", in a direction transverse to the plane of the circle of the arc with the chord of the arc disposed farthest from said point, and the interior surface of one side wall of the channel being generated by the like movement and disposition of the arc of a circle "x" at the end of a radius "y" about a point "z", where "x" and "y" represent greater values than "a" and "b" respectively and where "c" and "z" are adjacent and not coincident.

20 15. In a vise as defined in claim 1, the pipe bending die head being of substantially open channel-shape in cross-section and segment shape in plan, the interior surface of the bottom wall of the channel being generated by the circular movement of an arc of a circle "x" at the end of a radius "b" about a point "c", in a direction transverse to the plane of the circle of the arc with the chord of the arc disposed farthest from said point "c", and portions of the interior side walls of the channel adjacent the top edges thereof being generated by the like movement and disposition of the arc of a circle "x" at the end of a radius "y" about a point "z", where "x" and "y" represent greater values than "a" and "b" respectively and where "c" and "z" are adjacent and not coincident.

25 16. In a vise as defined in claim 1, the die head having a pair of shoulders formed thereon adjacent one end thereof, said shoulders being adapted to serve as a measuring limit for articles bent around the head substantially as described.

30 17. In a vise, a base member, a relatively stationary jaw mounted on said base member, a frame member pivotally connected to said base member, a movable jaw mounted on said frame member, said frame member being movable about its pivotal connection to ward and from a position where said jaws

are cooperable, means for securing said frame member to said base member when said jaws are in cooperative position including a relatively stationary abutment on one of said members and a relatively movable abutment on the other of said members adapted to engage and release one another and to be moved toward and from the another, an arm secured adjacent said jaws to one side of the plane of their cooperation adapted to be secured by and between said base and frame members when they are secured together, and a pipe bending die head on said arm adapted to be disposed adjacent the opening between said jaws for cooperation therewith and to be secured in such position against displacement therefrom in one direction by one of said abutments when so disposed, for bending pipes and the like.

35 18. In a vise, a base having a stationary jaw, a frame pivotally mounted on said base for swinging movement relative thereto, a movable jaw on said frame, an arm having a recess therein pivotally secured to said base to the rear of and in spaced relation to said stationary jaw adapted to cooperate herewith to serve as an auxiliary holding means for pipes and the like held between said jaws and to be swung out of cooperative relation therewith, and a fixed abutment on said base at the end of the radius length of said arm for securing said arm against radial movements from its pivot when in cooperative relation with said jaws.

40 19. In a vise, a base carrying a jaw, a frame carrying a second jaw and pivotally secured to said base for swinging movements into and out of a position with respect to the first said jaw where said jaws are cooperative, one of said jaws being movable, means for securing said jaws in cooperative relation, and a pipe bending die pivotally secured to said base for movements bodily toward and from a position adjacent the openings between said jaws and adapted to be secured against movement from such position when said jaws are secured in cooperative relationship.

45 20. In a vise, a base member having a jaw, a frame member including a second jaw pivotally secured to said base member for swinging movements into and out of such position with respect to the first said jaw where said jaws will cooperate with one another, means for securing said jaws in cooperative relation, a pipe bending die pivotally secured to said base for movements bodily toward and from a position adjacent the opening between said jaws and adapted to be secured against movement from such position when said jaws are secured in cooperative relationship to one another, and means connected to one of said members for securing said die in said position adjacent the opening between the jaws.

when said jaws are secured in cooperative relation to one another.

21. In a vise, a base having a stationary jaw, a frame pivotally mounted on said base for swinging movements relative thereto, a movable jaw on said frame, an arm having a recess therein secured by a pivot to said base to the rear of and in spaced relation to said stationary jaw and adapted to cooperate with said jaws to serve as an auxiliary holding means for pipe and the like held between said jaws and to be swung out of cooperative relationship therewith, and a fixed abutment on said base adjacent the end of the radius length of said arm for securing said arm against movements in one direction about said pivot when said arm is in cooperative relation with respect to said jaws.

22. In combination with a vise having means for securing a portion of an article to be bent while it is being bent, a bending die secured adjacent said securing means, said die having a head of substantially open front channel shape in cross-section and segment shape in plan, the interior surface of the bottom wall of said channel being generated by the circular movement of an arc of a circle "a" at the end of a radius "b" about a point "c", in a direction transverse to the plane of the circle of the arc with the chord of the arc disposed farthest from said point, said point being located behind the channel, and the interior surface of one side wall of the channel being generated by the like movement and disposition of the arc of a circle "x" at the end of a radius "y" about a point "z", where "x" and "y" represent greater values than "a" and "b", respectively, and where "z" is also located behind said channel but not coincident with "c".

23. In combination with a vise having means for securing a portion of an article to be bent while it is being bent, a bending die secured adjacent said securing means, said die having a head of substantially open front channel shape in cross-section and segment shape in plan, the interior surface of the bottom wall of said channel being generated by the circular movement of an arc of a circle "a" at the end of a radius "b" about a point "c" behind said channel, in a direction transverse to the plane of the circle of the arc with the chord of the arc disposed farthest from said point "c", and portions of the interior side walls of the channel adjacent the top edges thereof being generated by the like movement and disposition of the arc of a circle "x" at the end of a radius "y" about a point "z", where "x" and "y" represent greater values than "a" and "b" respectively, and where "c" and "z" are adjacent and not coincident.

24. In combination with a vise having means for securing a portion of an article to be bent while it is being bent, a bending die

secured adjacent said securing means, said die having a head of substantially open front channel shape in cross-section and segment shape in plan, the interior surface of said channel at its bottom substantially from end to end of said head being generated by the circular movement of an arc of a circle "a" at the end of a radius "b" about a point "c" located behind the channel, in a direction transverse to the plane of the circle of the arc with the chord of the arc disposed farthest from said point, and portions of the interior surfaces of the side walls of the channel above said bottom being generated by the like movement and disposition of the arc of a circle "x" at the end of a radius "y" about a point "z", where "x" and "y" represent greater values than "a" and "b" respectively, and where "z" is located behind said channel.

25. A bench vise for clamping hollow articles such as outlet boxes and the like comprising a base, a clamping member pivoted thereto, a projection on said base adapted to engage an interior portion of a hollow article, a second member connected for pivotal movements relatively to said clamping member, a projection on said second member arranged to engage another portion of the interior of a hollow article, and means for moving said clamping member to spread said projections to engage a hollow article therebetween.

26. In a bench vise, a relatively stationary base, a clamping member carried by said base for relative movements toward and from said base, means for limiting the movement of said member toward said base, a projection secured to said base constructed to engage the interior of a hollow article, a projection secured to said member constructed and disposed to engage another portion of the interior of a hollow article, and means mounted on said member and cooperating with said first named means for moving said projections away from one another when the limit of movement of said member and said base toward each other has been reached.

27. In a bench vise, a relatively stationary base, a clamping member connected to said base for relative movements toward and from said base, a second member connected to said first member and movable relative thereto, a projection on said base for engaging the interior surface of a hollow article, a projection on one of said members for engaging another portion of the inner surface of a hollow article, means for holding one of said members stationary with respect to said base, and means for moving the member having said projection thereon in such a manner as to move its projection away from the projection on said base when the other member is held stationary with respect to said base.

28. A bench vise comprising a base having

means thereon for attachment to a bench, a substantially flat stationary abutment secured to and projecting laterally of said base, a movable abutment carried by said base for movement toward and from said stationary abutment, said abutments being constructed and disposed to engage substantially opposite interior portions of the sides of a hollow article such as an outlet box or the like, and means for moving said movable abutment toward and from said stationary abutment for releasing and securing said articles.

In witness of the foregoing I affix my signature.

CERTIFICATE OF CORRECTION.

Patent No. 1,772,899.

Granted August 12, 1930, to

MARTIN E. JOHNSON.

It is hereby certified that error appears in the printed specification of the above numbered patent requiring correction as follows: Page 5, line 91, claim 18, for the word "herewith" read therewith; page 6, line 130, claim 28, after the article "a" second occurrence insert substantially flat, and page 7, line 2, same claim, strike out the words "substantially flat"; and that the said Letters Patent should be read with these corrections therein that the same may conform to the record of the case in the Patent Office.

Signed and sealed this 21st day of October, A. D. 1930.

M. J. Moore,
Acting Commissioner of Patents.

(Seal)
